UNITED STATES PATENT OFFICE

2,194,916

BRUSH

Edward B. Somers, Darby, Pa.

Application May 19, 1938, Serial No. 208,872

3 Claims. (Cl. 15—114)

My invention relates to brushes. The widest use of the brushes of the present invention is expected to be for cleaning type of typewriters and the like.

5 A purpose of the invention is to provide a brush having a spirally progressing cotton or other absorbent applicator mounted upon a wire handle.

10 A further purpose is to provide a brush having spirally wound intertwined rows of bristles and cotton or other suitable absorbent material.

15 A further purpose is to provide a brush having spirals of bristles and absorbent material, intertwined, the bristles forming facings for axial walls of the absorbent material.

Further purposes will appear in the specification and in the claims.

In the drawing I have preferred to illustrate one form only of my invention, selecting a form 20 which is efficient and inexpensive and which well illustrates the invention.

Figure 1 is a side elevation of my brush and its bottle closure cap support.

25 Figure 2 is a section of the spiral of bristles taken upon line 2—2 of Figure 1, the section being intended to follow the spiral.

Figure 3 is a section upon the line 3—3 of Figure 1, similar to Figure 2 but showing a row of cotton.

30 Figures 4 and 5 are side elevations showing, one, the bristles only, and the other, the absorbent material only of the two used in my invention.

Figure 6 illustrates my brush with a slight 35 modification of the arm.

Heretofore brushes for use to clean the type or platens of typewriters, adding machines and similar mechanisms have provided spiraled generally continuous stiff bristles and separate applicators to be used in conjunction with some cleaning agent. This has not proven wholly satisfactory because it has been necessary to use the applicator and bristles separately or to have a non-uniform and discontinuous operation.

40 The present brush is rigid with a bottle closure. It has alternate helical rows of cotton, or other suitable absorbent material, and hard bristles facing both axial sides of the cotton. The cleaning fluid is thus applied nearly simultaneously 45 with the brushing, producing a most satisfactory result.

In the drawing, 10 is a bottle closure cap of any suitable design or material supporting a twisted wire handle 11, within a boss 12, integral 50 with the cap.

The wire handle 11 comprises two strands of wire 13 and 14 twisted about each other and at the lower end 15 gripping a cleaning brush 16.

The cleaning brush is made up of bristles 17 5 and absorbent material 18, shown and described in this instance as soft cotton threads.

In the formation of the brush a wire 13 is placed in a suitable die (not shown), and layers, one of bristles and the other of cotton thread, 10 are laid across it. A second wire 14 is then placed above the layers and the two wires are twisted about each other. The cotton threads and bristles are thus formed in a helical brush in which the stiffness of the bristles causes them 15 to form facings 19 and 20 for the opposite axial helical surfaces of the spiral 18 of cotton. The groove or gutter between is thus also bounded or limited by walls 19 and 20 of bristle. Conveniently the two wires described above are shown 20 in the drawing as one wire bent back upon itself.

The twisting operation also forms the handle. The cleaning brush can be made with the spiral 25 rib of bristles and cotton threads close together or spaced at any suitable distance apart by the control of the quantity or volume of cotton and of bristles and the number of twists per inch of linear dimension of the brush length.

Figures 4 and 5, elements of my brush, Figure 4 showing it as it would exist if bristles only were 30 used, the spiral space or gutter between the spiraled bristles being the gutter of the finished brush. Figure 5 shows the winding of the cotton strands only. It fills up the space 21 between the helical turns of bristle so that both axial 35 faces of the cotton are covered by bristles. Considering the combined cotton and bristle helix as an advancing helical rib, the individual bristles pass through between the wires and extend one end 22 of each bristle to form part of the facing 40 of what, with respect to the direction 24 of rib advance, may be considered the back wall 23 of one helical rib and the other end 25 of each bristle to form part of the front wall 26 of an adjoining helical turn 27 of the rib. 45

For ease of application to some difficult type platens I have formed the handle of my brush with an offset 28, which is seen in Figure 6.

The cotton threads will absorb and carry sufficient cleaning fluid to the type, and the brush, 50 being of stiff bristles, will immediately come into contact with the type after the cleaning fluid has been applied, and before it can vaporize.

In both directions of longitudinal brush movement each spiral turn of my brush presents to 55

type or to other parts to be cleaned, first a relatively dry rim of bristle, then the intermediate cotton which carries the solvent cleaning liquid and, finally, a rim of bristles. And in each direction of movement the final rim of bristles is free to yield into the spiral groove or gutter space 29 and to discharge into this spiral groove the dirt which it has removed.

It will be evident that both the bristles and the cotton threads pass through between the twisted wires to form opposite sides of coaxial grooves, each having a different one of the wires at its bottom. The one groove which shows in the drawing has facings of bristle on opposite sides, and the other, an intervening spiral "groove" with facings of cotton. Because of the stiffness of the bristles they maintain their positions seen, form facings for the cotton, and provide the open groove seen in the drawing, whereas because of its tendency to spread the cotton on the two sides of what would otherwise show as a coaxial intervening spiral groove in the brush fills up the groove which it "faces" and gives the appearance of a full thickness or rib of cotton instead of edgings of cotton. The second "groove" with a wire at its bottom, therefore, does not show as a groove at all but shows as the cotton core between bristles in the drawing.

30 The brush shows one wire only of the pair of twisted wires, at the bottom of the one groove only which appears. This groove lies between the facings of bristle and the other wire of the twisted pair is hidden by the mass effect of the 35 cotton.

In view of my invention and disclosure varia-

tions and modifications to meet individual whim or particular need will doubtless become evident to others skilled in the art to obtain all or part of the benefits of my invention without copying the structure shown, and I, therefore, 5 claim all such in so far as they fall within the reasonable spirit and scope of my invention.

Having thus described my invention what I claim as new and desire to secure by Letters Patent is:

1. In a brush, a twisted wire handle, and alternate rows of bristles and absorbent material held by the wires, the bristles forming supporting and protecting walls maintaining both faces of each row of absorbent material and each such 15 faced row being spaced from the next faced row.

2. In a brush for cleaning type or the like, layers of bristles and absorbent material, and twisted wires holding the bristles and absorbent material, forming helical rows of bristles and 20 absorbent material, the same bristles forming facings and supports for adjacent faces of adjacent rows of absorbent material.

3. A twisted wire brush for cleaning typewriters or the like comprising a twisted pair of wires, a continuous spiral of cotton threads and of bristles held together by the wires, opposite ends of the same bristles forming two spiral rows covering respectively the two oppositely directed adjacent axial faces of adjoining turns of the 25 cotton spiral and separated, one turn of the spiral from the next by one of the wires, thus providing a bristle faced cotton spiral with a clearing space in between the turns.
